UNITED STATES PATENT OFFICE.

GOTTFRIED PIETZKA, OF WITKOWITZ, MORAVIA, AUSTRIA-HUNGARY.

REGENERATIVE GAS-FURNACE.

SPECIFICATION forming part of Letters Patent No. 389,009, dated September 4, 1888.

Application filed March 21, 1888. Serial No. 267,939. (No model.)

To all whom it may concern:

Be it known that I, GOTTFRIED PIETZKA, a subject of the Emperor of Austria, residing at Witkowitz, Moravia, Empire of Austria, 5 have invented new and useful Improvements in Regenerative Gas-Furnaces, of which the following is a specification.

The object of the invention is to provide a new and improved gas-furnace applicable to all 10 reverberatory furnaces used for smelting pig metal, reheating, puddling, or other purposes.

The invention consists of gas-generators located directly at one end of the furnace and connected with the same, and of regenerators 15 provided with reversing-valves and connected with the ends of the furnace, so that the waste gases pass through the regenerators, after which the air from the outside is passed through the regenerators and into the furnace in connection with the gases from the generators. 20

The invention also consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a longitudinal sectional elevation of the improvement as applied to a puddling-furnace. Fig. 2 is a vertical cross-section of the same on the line *x-x* of Fig. 1. Fig. 3 is a sectional plan view with parts broken out. Fig. 4 is an enlarged transverse section 35 of the reversing mechanism. Fig. 5 is a plan view of the reversing mechanism, and Fig. 6 is an end elevation of the same.

The gas-generators A and A', of any approved construction, are preferably built only 40 on one end of the furnace, and are charged with coke or other fuel, and into which a hot or cold air blast is sent. For practical purposes I prefer to employ two generators in order to obtain a constant gas-supply which is not 45 affected by stoking. For working puddling-furnaces ordinary coal may be used. The generators work with a comparatively small depth of fuel—about six feet. The gases of 50 the fuel are slaked by means of limestone added to the fuel, and the liquid slag is drawn off without material difficulty at the lowest point, *a*. (See Fig. 1.)

The generators A and A' are connected by the narrow channel A² with the settling or cleaning chamber B, located directly above 55 the generators A and A', and serving to collect a considerable quantity of dust carried upward with the gases passing through the channel A². This dust can be easily removed while the furnace is in operation through the 60 doors located at the outside. The settling-chamber B connects by a narrow opening with the channel C, leading to the hearth E, connected with a second or direct heating-hearth, F, both being of any approved construction. 65 Into the channel C discharges the vertical channel D, supplying the necessary amount of hot air for the combustion of the gases on the hearths E and F.

The hearth F connects at its rear end with 70 the flue or channel G, provided with two horizontal valves, H and H', made of fire-clay and adapted to connect said channel G alternately with the hot-air regenerators L and L', located at the sides of the furnace below the floor, as 75 shown in Fig. 2. The waste gases are passed through one of the regenerators, while the air necessary for combustion on the hearths E and F passes through the other regenerator, which had previously been heated to about 800° centigrade by the waste gases. Each of the regenerators L and L' is of any approved construction, consisting, principally, of the chambers N and N', respectively filled in the usual manner with fire-brick, as shown in Fig. 2, 85 and of the flues O and O', respectively, which, with the chambers N and N', are also heated by the waste gases.

The regenerators L and L' are provided with the valves K J and K' J', respectively, made 90 of suitable refractory material, and each having one passage-way, as is plainly shown in Fig. 3. Between the two valves K and J and K' and J' is located the chimney M or M'. Flues N² lead to the valves K and K' from the 95 outside, so as to admit the necessary atmospheric air. When the valve H is open, the valve H' is closed, as shown in Fig. 3, and the valves K J and K' J' are in the position indicated in the same figure. Then the waste gases 100 from the hearth F pass into the regenerator L and through the chamber N and the channel O, and from the latter through the valve J to the chimney M, and from the chamber N through

the valve K also to the chimney M. The air necessary for combustion passes through the channel N² and through the valve K' into the chamber N' of the regenerator L', which had been previously heated in the same manner as the regenerator L, above described. The air passing through the chamber N' gets heated and passes at its rear end under the valve H' into the channel O', and from the latter through the valve J' into the channel D, from which it passes upward and mingles in the channel C with the gases from the gas-generators A and A'. The mixture of gases and air is then ignited on the hearth E and utilized in the usual manner, then passes to the other hearth, F, and from the latter the waste gases pass to the regenerator L, as above described. When the temperature of the regenerator L' sinks below a certain degree, the valves H and H' are reversed, and the valves K J and K' J' are likewise reversed by the mechanism illustrated in Figs. 4, 5, and 6. The cold air from the outside then passes through the channel N² and the valve K into the chamber N of the heated regenerator L, and from the said chamber N to the channel O, the valve J into the channel D, and is used in the same manner as above described in reference to the air heated by the regenerator L'. The waste gases from the hearth F pass into the channel G and to the channel O' and the chamber N', and from the latter through the valves K' and J' to the chimney M'.

By building the gas-generators A and A' directly under the furnace, I gain the advantage that the initial heat of the gases is not lost, the gases passing into the furnace at a temperature at about 600° centigrade. By this means the additional heating of the gases is rendered unnecessary, and the entire heat of the waste gases can be utilized for heating the air-supply, and the half of the waste gases need not be used, as heretofore, for heating the gases from the generators A and A'. This is an essential difference, and at the same time a considerable advantage, as compared with the usual heating arrangements. It will also be seen that no conduit-pipes for the gases are employed, and consequently also all inconveniences usually encountered by the use of such conduits—such as deposits of tar, &c.—are obviated. The escaping gases are divided in the flue G in such a manner that the greater part passes through the respective chamber N or N', while the remainder passes through the flue O or O' of the regenerators L and L'. The heat is almost all taken up from the gases as they pass away to the chimney, the temperature then being only about 250° centigrade.

The position of the two valves K and J or K' and J' of the regenerators L or L' is the same while the furnace is at work—that is, at right angles to the positions of those of the other regenerator. After changing the directions of the currents, the positions of the valves H and H' in the flue G and the positions of the valves J K and J' K' are reversed.

The four valves K J and K' J' are counterbalanced by weights P, carried by levers, which are for this purpose slightly raised out of their casings by means of a set of levers, R, S, and T, worked by hand, and then the valves are turned at an angle of ninety degrees by another set of levers, U, V, and W, after which they are again lowered by means of the first set of levers. This operation is effected in an extremely short time.

If the furnace is put out of action for repairs or other purposes, the heat in the regenerators L and L' can be kept up at a small expenditure of fuel, so that when the furnace is again put in action both regenerators L and L' are ready for use at once. For this purpose I provide a valve, x, made of fire-clay and located in the channel C. When this valve x is closed, the channels O and O' are cut off by suitable means, and after suitably adjusting the valves K, J, J', and K', and partly closing the valves H and H', then the heat from the generators A and A' passes through the channel D into the channels O O', and from the latter to the chambers N and N' of the regenerators L and L'.

A reverberatory furnace provided with this heating arrangement exceeds considerably in its capabilities the existing constructions of furnaces, with no less consumption of fuel, and the wear is reduced to a minimum, ranging between one-half and one and a half per cent.

Having thus fully described my invention, I claim as new and desire to secure by Letters Patent—

1. In a furnace, the combination, with gas-generators discharging into the front ends of the hearths, of air-regenerators located at the sides of the hearths and connected with the latter at their rear ends, said regenerators discharging heated air alternately into the front ends of the hearths, so that the gases from the generators are mixed with the heated air from the regenerators, substantially as shown and described.

2. In a furnace, the combination, with one or more hearths connected with each other, of a gas-generator discharging into the front end of the first hearth, air-regenerators located at the sides of the hearths, connected alternately with the rear ends of the last hearth, discharging heated air alternately into the front end of the first hearth, whereby the gases from the generator are mixed with the heated air of the regenerators before entering the hearths, substantially as shown and described.

3. In a furnace, the combination, with one or more hearths connected with each other, of a gas-generator discharging into the front end of the first hearth, air-regenerators located at the sides of the hearths, valved channels for establishing communication alternately between the last hearth and the rear ends of said regenerators, and reversing-valves located in channels in each of the regenerators to permit outside air to pass alternately

through the said regenerators and to the front end of the first hearth, substantially as shown and described.

4. In a furnace, a gas-generator, a hearth into the front end of which said generator discharges, air-regenerators at opposite sides of the hearth, valved channels leading from the rear ends of the hearth into the rear ends of the regenerators, return-flues leading from the rear ends of each regenerator to the front end of each hearth, an air inlet and outlet at the front ends of the regenerators, and valves controlling the return-channel and said air inlet and outlet channel, substantially as set forth.

5. The combination, with the gas-generating furnace and the hearth, into the front end of which said furnace discharges, of two air-regenerators at opposite sides of the hearth, and having valved channels at their rear ends communicating with the rear end of the hearth, return-flues leading from their rear ends to the front ends of said hearth, inlet-channels at their front ends, channels crossing and connecting said inlet-channels and return-flues, valves at the juncture of said channels and flues, and the outlets in said crossing-flues between the valves, substantially as set forth.

6. The combination, with the gas-generating furnace, the hearth in front thereof, the intermediate settling-chamber and the vertical air-channel discharging into the front end of the hearth, of the two air-regenerators at opposite sides of the hearth, valved channels leading from the rear end of the hearth into the rear ends of the regenerators, return-flues leading from said channels beyond their valves to the said vertical air-channel, air inlet and outlet channels at the front ends of the regenerators, and the reversing-valves for alternately closing the inlet-channels and directing the air from the regenerators to the outlets and valves for alternately directing the air of the return-flues to the said outlets and vertical air-inlet, and a reversing mechanism for said valves, substantially as set forth.

In testimony whereof I have signed my name to this specification in the presence of two subscribing witnesses.

GOTTFRIED PIETZKA.
